(57) CLAIM

The ornamental design for wooden basket, as shown and described.

DESCRIPTION

FIG. 1 is a perspective view of the wooden basket showing our new design;

FIG. 2 is a rear view thereof;

FIG. 3 is a left side view thereof;

FIG. 4 is a right side view thereof;

FIG. 5 is a front view thereof;

FIG. 6 is a top view thereof;

FIG. 7 is a bottom view thereof;

FIG. 8 is a perspective view of another embodiment of our design having an appearance identical to that of the first embodiment except for the presence of the indication of color contrast; and,

FIG. 9 is a perspective view of another embodiment of our design, having an appearance identical to that of the first embodiment except for the absence of a handle.
